TRUSS SUPPORT

Paul I. Rongved, Riverdale, N. Y., and Cyral P. Erwin, Houston, Tex., assignors to The Erwin-Newman Company, Houston, Tex., a copartnership

Application December 6, 1952, Serial No. 324,438

4 Claims. (Cl. 108—1)

1

This invention relates to improvements in truss supports generally and, more particularly, to improvements in truss supports adapted to support building roofs, bridge structures, and the like.

The primary aim and object of the present invention is the provision of a truss support, which is structurally similar to a cantilever type support, for buildings, roofs or bridge structures, which can be substantially shallower in depth for a given load carrying capacity to thereby provide a truss support which can be substantially reduced in weight and made more readily portable from the point of fabrication to the point of erection.

Another object of the present invention is the provision of a truss support of the above character which uses less steel, or other material used for the fabrication of the support, for a given load carrying capacity and also requires a lesser amount of labor for its handling and erection to thereby facilitate such handling and erection.

Another important object of the present invention is the provision of a truss support of the above character in which the deflection, at the outer unsupported end of the truss support, is substantially less than such deflection in the heretofore used cantilever type trusses. Pursuant to this object of the present invention, the truss support is so constructed and arranged that live load deflection will be counteracted by temperature deflection to thereby neutralize or partially neutralize such live load deflection. This inherent tendency to balance the deflection minimizes the downward deflection at the outer end of the truss support so that when said support is used in a hangar installation where the hangar doors are guided at their upper ends by structure associated with said outer end of the support, such guide structure can be made substantially shallower than in heretofore used constructions with the attendant advantages of saving material, reducing the weight at the outer end of the support, and facilitating the sliding movement of hangar doors guided by such structure.

Yet another object of the present invention is the provision of a generally improved truss support system of the above character which, in its preferred form, is assembled from components which are structurally simple and relatively easy to assemble and erect, and which system provides inherent substantial economies over prior art systems consistent with load carrying capacity.

The above and other objects, features and advantages of the present invention will be more fully understood from the following description considered in connection with the accompanying illustrative drawings.

In the drawings:

Fig. 1 is a schematic transverse view of an 60 hangar and are adapted to be slidably movable

2

airplane hangar utilizing the truss support system of the present invention;

Fig. 2 is an enlarged fragmentary elevational view of the encircled portion 2 of Fig. 1;

5 Fig. 3 is a sectional view taken on the line 3—3 of Fig. 2;

Fig. 4 is an enlarged fragmentary elevational view of the encircled portion 4 of Fig. 1;

10 Fig. 5 is a sectional view taken on the line 5—5 of Fig. 4;

Fig. 6 is an enlarged fragmentary elevational view of the encircled portion 6 of Fig. 1;

Fig. 7 is an enlarged fragmentary elevational view of the encircled portion 7 of Fig. 1;

Fig. 9 is an enlarged fragmentary elevational view of the encircled portion 9 of Fig. 1;

20 Fig. 10 is a sectional view taken on the line 10—10 of Fig. 9;

Fig. 11 is an enlarged fragmentary elevational view of the encircled portion 11 of Fig. 1; and

25 Fig. 12 is a sectional view taken on the line 12—12 of Fig. 11.

Referring to the drawings, and more particularly to Fig. 1 thereof, there is shown a hangar 10 for airplanes having a truss support structure 12 formed according to the present invention.

30 Although the support structure 12 is shown in association with hangar 10 it will be understood that such support structure may be used in any building structure or bridge structure and its utilization in hangar 10 is by way of example only. Hangar 10 may be constructed in any 35 desired manner and in the illustrated embodiment said hangar is of the double type being constituted by hangar portions 14 and 16 which are structurally similar and which are separated by the lean-to 18 which extends for the length of said hangar. The hangar 10 may be of any 40 desired length and Fig. 1 is illustrative of a transverse portion of said hangar showing the truss support 12 associated with such hangar. It will be understood that the hangar 10 will be 45 provided with a plurality of laterally spaced truss supports 12 with the number of such supports provided being in accordance with the hangar length. Each of the truss supports 12 is structurally similar and is associated with hangar 50 10 in a similar manner, and accordingly only one of such truss supports will be described in detail hereinafter. Each of the hangar portions or sections 14 and 16 is provided with sliding doors 20 which are adapted to be opened for ingress 55 and egress of airplanes in the hangar sections 14 and 16. It will be understood that the hangar doors 20 may be of any desired length and in the preferred embodiment such doors are provided in sections extending longitudinally of the

hangar and are adapted to be slidably movable

on tracks at their lower ends. The doors 20 are guided at their upper ends for slidable movement by structure to be described in detail hereinafter.

The truss support 12 comprises a balanced compression member 22, a cantilever member 24 which is secured thereto, and the rigid means 26 which is capable of taking compression or tension which in the illustrated embodiment is constituted by the member 28 and associated supporting structure which will be described in detail hereinafter. It will be evident that the truss support 12 extends transversely of the hangar section 14 for the full width thereof and that a plurality of such truss supports will be provided in laterally spaced disposition, said truss supports being adapted to support the hangar roof (not shown) of hangar section 14. Although the longitudinally extending inner member 22 in the preferred embodiment is a balanced compression member it is to be noted that in truss support 12 it is not essential that member 22 be a balanced compression member since other types of members will suffice for the accomplishment of the intended purpose. In this connection it will be noted that the member 22 is somewhat arched and is so shaped that the resultant force acting thereon creates forces in the top and bottom chords of truss 22 acting in the same direction and approximately equal in magnitude. Thus member 22 is a balanced compression member similar to an arch following the thrust line. The member 22 is framed together as in a conventional cantilever support so that the component members give mutual support and prevent distortion of the member, said member comprising a truss framework of straight members connected at their ends and having internal axial stresses either in tension or compression as the main forces to which they are subjected. Thus the member 22 is braced in any suitable manner by a plurality of diagonal rods 30 to produce the conventional triangulation illustrated in Fig. 1. Thus the balanced compression member 22 is structurally similar to a conventional cantilever support except that said member 22 is formed substantially shallower in depth than such conventional support for an equivalent load carrying capacity, for the reasons which will be fully brought out hereinafter.

With reference to Figs. 1 and 6, there is shown one possible manner of interconnection between member 22 and the upright support 32 of lean-to 18. The upright support 32 is preferably formed of a plurality of I-beam sections 34 which are joined together in end-to-end relation by means of the plates 36, said plates being suitably secured to said I-beam sections in any conventional manner, as by means of the rivets 38. Thus the upright support or column 32 is formed by suitably securing together a plurality of sections, said sectional arrangement being desired in order to minimize the transporting and handling problem. The inner end 40 of the member 22 is secured to the upright support 32 by means of the rocker joint 42. Although a rocker joint 42 is used in the preferred embodiment it will be apparent that any type joint may be utilized for this purpose and such joint may be of the "fixed" type. Thus the upright support 32 is provided with a fitting 44 secured thereto, said fitting having a planar face 46 which is adapted to cooperate with the arcuate face 48 of fitting 50 which is secured to the member 22. The fittings 44 and 50 are maintained in assembled

relation by means of the bolt 52 which passes through aligned apertures in such fittings.

The cantilever member or outer member 24 is formed structurally similar to the member 22 except that the former is not a balanced compression member. The members 22 and 24 are preferably formed by a plurality of angle members which are secured together to give mutual support and, although in the preferred embodiment the members 22 and 24 are formed as separate structures, it will be understood that if desired said members may be formed as one integral structure or may be formed of a greater number of components than that shown and described herein. The cantilever member 24 is adapted to be supported at its inner end 54 and its opposite end 56 is unsupported externally as in conventional cantilever supports.

With reference to Figs. 1, 2 and 4 there is shown the manner of interconnection between the members 22 and 24 of truss support 12, it being noted that members 22 and 24 are adapted to be assembled at the point of erection in the manner now to be described. The members 58 constitute part of the support member 22 whereas the members 60 constitute part of the support member 24, said members 58 and 60 being secured to the plate 62 in any desired manner, as by means of rivets and the like. Thus the securing of the angle members 58 and 60 of the members 22 and 24, respectively, to the support plate 62 is effective to maintain the upper part of members 22 and 24 secured together in fixed relation. In practice, the support plate 62 will be secured to the angle members 60 of member 24 at the point of fabrication and the angle members 58 of member 22 will be secured to said plate at the point of erection, it being noted that the member 24 constitutes the shorter section so that the securing of the plate 62 to said section will tend to balance the shipping load of the truss support 12 to the point of erection. The angle members 58' and 60' at the lower part of the members 22 and 24, respectively, are secured together in a similar manner through the intermediation of the plate 64. It will be noted that the vertical members 68 are secured to both plates 62 and 64, said members being designated as 60' at the lower ends thereof. With reference to Fig. 5 it will be noted that angle members 60' are constituted by a pair of angle members in side by side relation, it being understood that if desired members 22 and 24 may be similarly constituted in their entirety or may be formed by the interconnection of single angle members, or by any combination thereof. The lowermost angle members 58' and 60' are further secured together by means of the plate 66 which overlaps adjacent end portions of said members and is secured thereto in any conventional manner, as by means of rivets, or the like. In practice, the plates 64 and 66 will be secured, as by means of rivets, to the angle members 60' of cantilever member 24 and the angle members 58' of member 22 will be secured to said plates at the point of erection. From the above it will be apparent that the members 22 and 24 may be fabricated as one unitary structure or may be fabricated of a plurality of component parts and subsequently assembled in the aforescribed manner to produce the structure designated as 22 and 24 of the truss support 12. As afore pointed out the end 56 of member 24 is unsupported, said end being provided with the guiding structure 68 which is adapted to guide the sliding doors 20

at their upper ends. The truss support 12, which is structurally similar to a conventional cantilever type support, is substantially shallower in depth for a given load carrying capacity than such conventional support, which results from the utilization of the means 26 capable of taking compression or tension which partially supports the members 22 and 24 aforesaid and opposes turning moments of support 12 about joint 42 in two opposite directions. Thus the members 22 and 24 are substantially shallower in depth for a given load carrying capacity due to the integration with said members of the means 26 capable of taking compression or tension which contributes to the support of said members and opposes the turning moments thereof. The member 28 capable of taking tension or compression of the means 26 is constituted by a longitudinally extending I-beam, said member 28 being supported at one end 10 by the column 32, the opposite end 12 of said member being adapted to be secured to the members 22 and 24 at an intermediate point thereof, for example at the upper point of interconnection between the members 22 and 24.

With reference to Figs. 7 and 8 there is shown the manner of interconnection between the end 10 of the member 28 and an adjacent portion of the upper end of upright I-beam 32. The member 74 which is capable of taking compression or tension is also constituted by an I-beam and is interconnected at a common point with the interconnection of upright support 32 and the member 28. A pair of plates 76 are secured to the web portion 78 of member 74 in any suitable manner as by means of welding, riveting, or the like, said plates being adapted to receive therebetween the upright plate 80 which is secured to the base plate 82, the latter in turn being secured to the plate 84 which is suitably secured to the uppermost end portion of the upright support 32. The web portion 86 of the member 28 has secured thereto in any conventional manner a pair of filler plates 88, said filler plates having a pair of securing plates 90 secured thereto, said plates 90 being adapted to straddle the spaced plates 76 which are secured to member 74. The plate 80, the plates 76, and the plates 90 are provided with apertures which are adapted to be aligned in their properly assembled relation for the reception of the bolt 92, the latter being adapted to receive the nut 84 for maintaining the upright support 32 and the members 28 and 74 in assembled relation.

With reference to Figs. 1, 2 and 3 and as afore pointed out in detail, the support plate 62 is utilized for interconnecting the members 22 and 24 at their upper connection point. This same support plate 62 is also utilized for interconnecting one end of the member 28 to the interconnected members 22 and 24. More particularly, the web portion 86 of member 28 has secured thereto in any conventional manner a pair of filler strips or plates 98, said filler strips in turn being secured to the plates 100. Similarly, the plate 62 has a pair of plates 102 secured thereto, said pair of plates being adapted to be secured to the plates 100. The plates 100 and 102 and the support plate 62 are suitably apertured therethrough and said apertures are adapted to be aligned for the reception of the bolt 104 which is adapted to receive the nut 106 for effecting the securing of the member 28 to the plate 62 and consequently to the assembled members 22 and 24. Thus the plate 62 constitutes the con-

necting means for interconnecting members 22, 24 and 28, it being understood that said interconnection may be accomplished in any desirable manner and the specific interconnection aforesaid is merely by way of example and is not to be construed in any limiting sense.

With reference to Figs. 1, 9 and 10 there is shown the manner of interconnection between the member 74 and the members 108, 110 and 112, said members 108 and 110 being in the form of I-beams and constituting the means for the support of one end of member 74. Thus the members 108 and 110 are in the form of members capable of taking tension or compression and together with the member 74 and the upright support 32 constitute the support structure for the member 28. The web portion 78 of member 74 has secured thereto in any suitable manner a pair of filler strips 116, the latter having secured thereto in any desired manner the plates 118, said plates being adapted to be secured to the support plate 120 in a manner to be described hereinafter. The web portion 122 of the member 112 similarly has secured thereto a pair of filler strips 124, the latter having secured thereto the plates 126 which are in turn adapted to be secured to the support plate 120. Thus each of the members 74 and 112 are secured to the support plate 120 in a similar manner, the plates 118 and 126 being suitably apertured for the reception of the bolts 128 which pass through aligned apertures of the support plate 120, said bolts being adapted to receive nuts 130 for effecting the interconnection between members 74 and 112 through the intermediation of the plate 120. It will be understood that the apertures in the support plate 120 and plates 118 and 126 are adapted to be aligned for the through reception of bolts 128, the latter in conjunction with nuts 130 constituting the fastening means for effecting this interconnection. The members 108 and 110 are connected in mutual angular relation to the support plate 120, each of said members being connected to the plate 120 in a similar manner. The end 132 of member 108 has a flat plate 134 secured thereto in any desired manner, said plate in turn having an angle bracket 136 secured thereto. More particularly, the base 138 of the angle bracket 136 is secured to the plate 134 and the projecting or leg portion 140 of said bracket is secured to the plate 120 by means of the bolts 142. As aforesaid the member 110 is similarly connected to the support plate 120 through the intermediation of a plate 134 and bracket 136.

With reference to Figs. 1, 11 and 12 there is shown the specific manner of interconnection between the lower end portion of members 108 and 110 and the longitudinally extending horizontally disposed I-beam member 144 which constitutes an upper supporting member of lean-to 18. It will be apparent that the member 144 opposes the horizontal component of the force of the member 22 against the column 32. The I-beam member 144 is provided with an end plate 146 as best shown in Fig. 6, said end plate being secured to the upright column 32 adjacent to the point of interconnection between said column and member 22. The members 108 and 110 are secured to the member 144 in spaced sea-leg relationship and each of the interconnections between the members 108 and 110 and the horizontally disposed member 144 is accomplished in a similar manner so that the interconnection between the members 108 and 144 only will be specifically described. The lower end

146 of the member 108 is secured to one leg 148 of the bracket 150, said leg 148 being secured to the web portion 152 of the member 108 in any desired manner, as by means of bolts and nuts 154 and 156, respectively. The base portion 158 of the bracket 150 is secured to an adjacent portion of the face 160 of the member 144, said securing being effected by means of the bolts 162.

The member 112, which is capable of taking tension or compression, is structurally similar to the member 74 and is associated with the truss support 12' in the same manner that the member 74 is associated with the truss support 12. The members 108 and 110 also constitute support means for the member 112 and it will be readily apparent that the inventive concept herein disclosed is equally applicable for utilization with a single hangar section 14. Thus truss support 12 may be used in association with a single hangar section 14 in which case the member 112 and its associated structure utilized for the support of the truss support 12' will be dispensed with. The means 26 which is capable of taking tension or compression as herein described and illustrated for hangar section 14 is constituted by the member 28 and structure utilized for the support of said member, said structure being the members 74, 108 and 110 and the I-beam upright column 32. Thus the column 32 and members 28, 74, 108 and 110 are members which are capable of taking tension or compression which are adapted to aid in the support of the integrated structure constituted by the members 22 and 24 whereby the latter members can be substantially shallower in depth for a given load carrying capacity than conventional cantilever arrangements. It is to be noted that the inclined I-beam member 28 may be supported in any desired manner and that the specific support means aforescribed and constituted by the members 74, 108 and 110 and column 32 is given merely by way of example. Thus the member 28, which is secured to the members 22 and 24 at a point spaced from the joint 42, may have its end 70 supported in spaced relation relative to said joint in any desired manner. From the above it will therefore be apparent that the member 28 constitutes the principal support member of the means 26 which is capable of taking tension or compression and that the structure associated with the end 70 of member 28 constitutes structure of means 26 which is utilized for the support of the end 70 of member 28. Thus the truss support 12 is supported at joint 42 and is supported at a point spaced therefrom by the means 26 which is capable of taking tension or compression and more specifically by the end 72 of the member 28. The member 28 has its end 70 arranged in relation to the joint 42 and the point of interconnection between the members 22 and 28 so that a large lever arm is provided by column 32, said lever arm extending between the point of interconnection 42 and the point of interconnection between member 28 and column 32. Thus the portion of the column 32 between the adjacent ends of the members 22 and 28 and their point of interconnection with the upright support 32 constitutes a large lever arm for the support of members 22 and 24 to thereby enhance the supporting characteristics of the means 26. It is to be noted that lean-to 18 and associated structure constitute vertical supporting means for truss support 12, and that the means 26 which is capable of taking tension or compression is disposed above truss 12 and is secured thereto at a point spaced from joint 42 whereby to oppose turning

moments of said truss in either of two opposite directions about said joint. Although specific interconnections between the members of the truss support system have been illustrated and described, it will be understood that any suitable interconnections may be used.

As afore pointed out the member 22 of the support 12 is preferably constructed as a balanced compression member although it will be understood that said member need not be a balanced compression member in the system aforescribed. The deflection at the end 56 of the truss support 12 is substantially less than the deflection in the heretofore used cantilever type trusses, this feature being achieved by constructing and arranging the live load deflection as to be counteracted by temperature deflection to thereby neutralize or partially neutralize the live load deflection. For example, under certain climatic conditions thereof hangar 16 would be weighted down by snow deposited thereon which would be effective to deflect the end 56 of support 12 downwardly, as will be readily apparent. Under such conditions the member 28 which is outside of the hangar proper would contract due to the lower atmospheric temperature whereas the members 22 and 24 would not so contract and might even expand depending on the temperature in the hangar. Thus the live load deflection at the end 56 of support 12 would be counteracted by the temperature deflection aforesubussed so that these two tendencies act in opposite directions to thereby neutralize each other or partially neutralize each other. Consequently the deflection due to the live load under the above noted conditions is compensated for, either wholly or partially, by the deflection due to temperature variation and the deflections of the live load and the deflections due to temperature variation will never be in the same direction but on the contrary will always act in opposite directions to thereby tend to neutralize each other. This balanced deflection feature permits the guiding structure 68 for the hangar doors 20 to be substantially shallower than in the heretofore used constructions with the attendant advantages of saving material, reducing the weight at the outer end of support 12, and facilitating the sliding movement of hangar doors 20 guided at their upper ends by the guiding structure 68.

Thus the truss support 12 which is structurally similar to a cantilever type support can be substantially shallower in depth for a given load carrying capacity so that the support 12 can be substantially reduced in weight and made more readily portable from the point of fabrication to the point of erection. As afore pointed out the means 26 which is capable of taking tension or compression, constituted by the member 28 and associated support structure, aids in the support of the unitary structure constituted by the members 22 and 24 whereby said unitary structure can be made substantially shallower as aforescribed. The means 26 which is capable of taking tension or compression is constituted by I-beam members which have the characteristic of withstanding both tension and compression forces depending on the forces acting on the unitary structure constituted by the members 22 and 24. Thus when downward forces are applied to truss support 12 the member 28 will oppose a counter-clockwise moment of support 12 about joint 42 and will have tension stresses applied thereto whereas when upward forces are applied to said support compression stresses will be set up in member 28

to oppose a clockwise moment of support 12 about joint 42, as will be readily apparent. The support structure aforescribed in detail is preferably fabricated of steel utilizing conventionally shaped structural members although it will be understood that such members may be constructed of any of the well known structural materials and may be shaped in any desired manner. The truss support 12, in its preferred form, is assembled from components which are structurally simple and relatively easy to assemble and erect, and which support provides inherent substantial economies over prior art supports consistent with load carrying capacity. It will be readily apparent that members 22 and 24 are substantially shallower in depth for a given load carrying capacity than a conventional cantilever type support due to the integration with said members of the means 26 which is capable of taking compression or tension whereby there is obviated the need for forming said members of such weight as to provide sufficient deadload to oppose a clockwise moment of said members about joint 42. Further it is to be noted that member 22 is acted upon by a resulting reaction at each end and primarily by transverse forces over the length thereof, said reactions and forces creating a thrustline similar to an arch. There may exist more than one thrustline depending on the various loading conditions and by shaping member 22 so that the top chord is above and the bottom chord is below such thrustline or thrustlines, a maximum economy of materials is achieved and said member will be of minimum depth.

While we have shown and described the preferred embodiment of our invention, it will be understood that various changes may be made in the present invention without departing from the underlying idea or principles of the invention within the scope of the appended claims.

Having thus described my invention, what I claim and desire to secure by Letters Patent is:

1. In a structure, vertical supporting means, a truss secured at its inner end to said vertical supporting means and projecting outwardly therefrom, and means for suspending said truss from said vertical supporting means comprising rigid means capable of taking compression or tension disposed above said truss and secured to the latter at a point spaced from said inner end of the truss for opposing the turning moments of the truss in either of the two directions about the point of said securement of its inner end to said vertical supporting means, said rigid means capable of taking tension or compression comprising a member secured to said vertical supporting means at a point spaced upwardly from the top of the truss at the inner end thereof and extending from said last mentioned point to said point of securement to the truss, said truss having a cantilever section projecting outwardly beyond said point at which said rigid means capable of taking tension or compression is secured to said truss.

2. In a structure, vertically extending supporting means, a truss secured at its inner end to said vertically extending supporting means and projecting outwardly therefrom, and means for suspending said truss from said vertically extending supporting means comprising rigid means capable of taking compression or tension disposed above said truss and secured to the latter at a point spaced from said inner end of the truss for opposing the turning moments of the truss in either of the two directions about the point of said securement of its inner end to said vertically

extending supporting means, said means capable of taking tension or compression comprising a member having an inner end secured to said vertically extending supporting means at a point spaced upwardly from the top of the truss at the inner end thereof and extending from said last mentioned point to said point of securement to the truss, said vertically extending supporting means having a part disposed laterally and downwardly of said inner end of said first mentioned member, and a rigid member connected to said inner end of said first mentioned member and connected to said part of said vertically extending supporting means, at least part of said truss being a balanced compression member extending longitudinally of the truss between its inner end and the point at which said rigid means capable of taking compression or tension is secured to the truss.

3. In a structure, a truss, means for supporting said truss at the inner end thereof at a point vertically spaced from the lower end of said supporting means, and rigid means capable of taking tension or compression disposed above said truss and secured to the latter at a point spaced outwardly from said first mentioned point, said rigid means capable of taking tension or compression comprising a member secured to said first mentioned means at a point spaced upwardly from said truss at the inner end thereof and extending from said last mentioned point to said outwardly spaced point, said truss comprising framework members connected to each other, said means which is capable of taking compression or tension acting on said framework as a unit to oppose the turning moments of said framework in either of two opposite directions about said first mentioned point.

4. In a structure, a truss, means for supporting said truss at the inner end thereof at a point vertically spaced from the lower end of said supporting means and rigid means capable of taking tension or compression disposed above said truss and secured to the latter at a point spaced outwardly from said first mentioned point, said rigid means capable of taking tension or compression comprising a member secured to said first mentioned means at a point spaced upwardly from said truss at the inner end thereof and extending from said last mentioned point to said outwardly spaced point, said truss comprising framework members connected to each other and having internal axial stresses either in tension or compression as the main forces to which they are subjected, said means which is capable of taking compression or tension acting on said framework as a unit to oppose the turning moments of said framework in either of two opposite directions about said first mentioned point, said means for supporting said truss comprising a vertical column to which said member is anchored at said inner end thereof, said vertical column being subjected to the horizontal component of the force of said truss thereagainst, and means for opposing said horizontal component of the force of said truss against said column.
